UNITED STATES PATENT OFFICE.

GIDEON PILLOW BROWN, OF LAKE BLUFF, ILLINOIS, ASSIGNOR TO COMBUSTION IMPROVEMENT COMPANY, OF CHICAGO, ILLINOIS, A CORPORATION OF DELAWARE.

DEVICE FOR CAUSING COMBUSTION OF FURNACE-GASES.

1,287,864.

Specification of Letters Patent.

Patented Dec. 17, 1918.

Application filed February 7, 1917. Serial No. 147,068.

To all whom it may concern:

Be it known that I, GIDEON PILLOW BROWN, a citizen of the United States of America, and resident of Lake Bluff, Lake 5 county, Illinois, have invented a certain new and useful Improvement in Devices for Causing Combustion of Furnace-Gases, of which the following is a specification.

My invention relates to devices for injecting hot air into the products of combustion in a furnace, for the purpose of causing combustion of the inflammable gases that escape from the fuel on the grate, and which are employed in this manner, for example, to increase the efficiency of a steam 10 plant, the result being that smoke is prevented, to a large extent, by the burning of the gases, and that a consequent reduction in the consumption of fuel is accomplished 15 by reason of the more perfect combustion produced in the furnace.

Generally stated, the object of my invention is to provide means whereby the air is more effectively and more highly heated 20 than heretofore, before being injected into the gases and products of combustion, so that the inflammable gases will be ignited and burned with an intense heat.

A special object is to provide a device 25 of this kind in which means are provided for rendering the device self-heating in character, by causing a thorough combustion of the inflammable gases near the surface of the device, so that the air will be very 30 highly heated by the combustion of said gases before the air and gases are combined.

Another object is to provide an improved 35 construction and arrangement for retarding the passage of the air through said device, so that the air will be given ample time in which to become highly heated, and whereby a sufficient amount of radiating 40 surface will be insured within said device to properly heat the air.

To these and other useful ends, my invention consists in matters hereinafter set forth and claimed.

In the accompanying drawings:—

Figure 1 is a longitudinal section of a steam-boiler-furnace provided with a device 45 for injecting hot air into the gases escaping from the fuel in the combustion-chamber, embodying the principles of my invention.

Fig. 2 is an enlarged bottom plan-view of 55 said device, showing certain portions thereof in section to illustrate the construction.

Fig. 3 is a horizontal section on line 3—3 in Fig. 4.

Fig. 4 is a vertical section on line 4—4 60 in Fig. 3.

As thus illustrated, the furnace shown in Fig. 1 may be of any suitable, known or approved construction. As illustrated, this furnace is of the kind ordinarily known as 65 a Babcock & Wilcox steam-boiler-furnace, being provided with water-tubes A which are inclined upwardly at their forward ends, so that the water circulates in the usual and well-known manner. The combustion-chamber has the usual grate B upon which the fuel is burned. The water-tubes have vertically disposed baffle plates 1 and 2, so that the boiler is divided into three passes, in the well-known manner, whereby the products of combustion escape upward through 70 the first pass and then downward through the second pass and then upward through the third pass, as indicated by the arrows, before escaping into the stack or chimney. 75

The device for injecting heated air into the gases and products of combustion can be of any suitable form or character, but with the boiler and furnace shown and described, this device is preferably in the 85 form of a hollow disk C supported directly above the first pass of the boiler, at a distance from the fire, so that the products of combustion and unburned gases travel upward from the grate and come directly in 90 contact with said device before descending through the second pass of the boiler. The air-supply-pipe c can be supported in any suitable manner. The device C should be made of some material which will not be 95 destroyed by the fire, such as fire-clay, and is preferably constructed as shown in Figs. 2, 3 and 4, being provided interiorly with a plurality of concentric rows of curved baffle-plates 3, with openings 4 which form 100 the gaps or breaks in the circles on which the said plates are located. The bottom of the hollow disk C is provided with a boss 5 to receive the upper end of the pipe C, and the annular periphery of said device is provided with outlets 6 for the heated air. The air becomes highly heated while passing 105 through the disk C, as the baffle-plates 3

retard the flow of the air and provide sufficient radiating surface to properly heat the air, so that when the air escape through said openings 6, it is heated to the temperature necessary for causing ignition of the inflammable gases forming part of the products of combustion.

In order, however, to insure a sufficiently high temperature for the air, passages 7 extend from some of the openings 6 downward and then toward the center of the disk on the under side thereof (see Fig. 2), and the side walls of these passages on the under side of the disk are provided with outlets 8, so that small jets of air are produced on the bottom of the disk. This will ignite the inflammable gases immediately below the disk C, causing intense heat at this point, so that a portion of the inflammable gases will be used by the device to maintain the necessary high temperature thereof. The highly heated air escaping from the outlets 6 will produce combustion of the inflammable gases, but it will be seen that this combustion occurs in greater part above the disk C, as the gases are ignited around the periphery of the disk and then pass in burning condition above the disk and downward between the tubes of the boiler. The jets of hot air escaping from the openings 8, which are smaller than the openings 6, however, encounter the gases which strike the bottom of the disk C, and in this way some of the gases are burned with intense heat immediately below the disk C, thereby causing the latter to be self-heating in character. The jets formed by the openings 6 are longer, of course, than the jets formed by the openings 8.

As stated, the disk C can be made of any suitable material, and when made of fire-clay, as previously suggested, can be constructed in the following manner: The body of the disk C can be divided into upper and lower halves, each half being molded separately, and the upper half can then be accurately placed on the lower half, and the two parts can then be secured or united in any suitable manner.

Any suitable means can be employed for supplying the air to the pipe c, but ordinarily the natural draft of the furnace is sufficient to draw the air through the disk C, causing it to escape fast enough and in sufficient volume to produce the desired combustion of the inflammable gases. It is obvious, however, that the air can be supplied under pressure, if such is necessary or desirable.

While the invention has been illustrated in connection with a Babcock & Wilcox boiler, it will be understood that the invention is applicable to the so-called Heine or Scotch boilers, and to furnaces in general, wherever it may be desirable to increase the efficiency 65 by an influx of hot air to burn the uncon-

sumed gases which escape from coal or other fuel on the grate. As shown, the device is in the form of a hollow disk C, as explained, but the shape and form of this air-heater can be changed or varied to suit the requirements of different kinds of furnaces, in various ways, without departing from the spirit of my invention.

Furthermore, the self-heating means (the means whereby the device is self-heating) 75 consists, as shown, of air-jets on the under side of the hollow disk, but the construction in this respect can be changed or modified to suit the requirements, and I do not limit myself to the exact construction shown and described. It will be seen that the invention involves the provision of air-jets for heating the device, the openings for these jets being so arranged that they sweep the surface of the body whereby the jets of air are directed 80 along said surface. It is also true, in the construction shown and described, that these jets for heating the hollow body are so arranged that they impinge directly upon different portions of the body itself, as the air-jets from the openings 8 of one passage 7 will shoot across the lower surface of the disk and impinge upon the side wall of the adjacent passage 7, thereby causing a combustion of the gases between the radially arranged ribs containing the passages 7 on the under side of the body.

It will also be seen that the air outlets 9 at the inner ends of the ribs containing the passages 7 are in such position that jets of air 100 are directed inwardly against the boss 5 of the hollow body or disk C, so that a combustion of the inflammable gases will be caused immediately around said boss.

With the foregoing construction, it will be 105 seen that the outlets or discharge openings 6 constitute a main set of openings for the major discharge of the heated air, while the openings 8 and 9 constitute an auxiliary set of openings to produce the minor discharge 110 of heated air, whereby the device is self-heating in character, as previously explained. Furthermore, it will be seen that a group of auxiliary openings is allotted to each passage leading thereto, these passages 115 being provided by the ribs 7, so that the air remains longer in the device before reaching the auxiliary openings than before reaching the main openings, and is heated in the ribs 7, before escaping from the auxiliary openings, as well as within the body of the device itself, whereby the minor discharge of air is of high temperature to produce the heat necessary to keep the device more highly heated than would be the case if only 120 the openings 6 were provided for the discharge of the air.

What I claim as my invention is:—

1. In a device of the class described, in combination with a furnace having a com- 130

- bustion chamber, a hollow member located a distance from the fuel zone and disposed in position to inject heated air into the unburned gases passing off with the products of combustion and having self-heating means in the form of hollow ribs on the surface of said body, each rib having lateral air-jet openings to maintain a combustion of the gases immediately adjacent said member, so that said member will be maintained at the temperature necessary for heating the air, each rib having an inlet communicating with the interior of said member, and a connection to supply air to said member.
2. In a device of the class described, in combination with a furnace having a combustion chamber, a hollow member located a distance from the fuel zone and disposed in position to inject heated air into the unburned gases passing off with the products of combustion and having self-heating means in the form of radial hollow ribs on the under surface of said body, each rib having lateral air-jet openings to maintain a combustion of the gases immediately adjacent said member, so that said member will be maintained at the temperature necessary for heating the air, and a connection to supply air to said member, said ribs having inlets which communicate with the interior of said member, and said member having outlets.
3. In a device of the class described, in combination with a furnace having a combustion chamber, a hollow member located a distance from the fuel zone and disposed in position to inject heated air into the unburned gases passing off with the products of combustion and having self-heating means to maintain a combustion of the gases immediately adjacent said member, so that said member will be maintained at the temperature necessary for heating the air, said member having main outlets for the air, and said means comprising radial hollow ribs on one surface of said member communicating with the interior thereof, each rib having air-jet openings from which the jets of air sweep said surface, and a connection to supply air to said member.
4. In a device of the class described, the combination of a furnace having a combustion chamber, a hollow member located a distance from the fuel zone and disposed in the path of the draft to inject heated air into the unburned gases passing off with the products of combustion, having a main set of openings for a major discharge to supply the heated air to the gases to cause combustion thereof in said chamber, and having an auxiliary set of openings for a minor discharge to maintain a combustion of the gases immediately outside of and close around said member, to increase the temperature thereof, so that said device will be self-heating to maintain the air at the temperature necessary to cause ignition of the unburned gases and products of combustion while carried along by the draft, and means to supply air to said hollow body.
5. A structure as specified in claim 4, in which the openings of the main set are larger than those of the auxiliary set of openings, so that long jets are formed by the main openings and short jets by the auxiliary openings.
6. A structure as specified in claim 4, and means inside thereof to distribute the air to both sets of said openings substantially as shown and described.
7. A structure as specified in claim 4, and passages leading to said auxiliary openings, there being a group of auxiliary openings for each passage, whereby each passage leads to a separate group of auxiliary openings, and so that the air travels farther and remains longer in said device before reaching said auxiliary openings than before reaching said main openings, and openings to discharge the air from said body into said passages.

Signed by me at Chicago, Illinois, this 24th day of January, 1917.

GIDEON PILLOW BROWN.
